US00D831816S

(12) **United States Design Patent** (10) **Patent No.:** **US D831,816 S**
Baek et al. (45) **Date of Patent:** **** Oct. 23, 2018**

(54) **FAN**

(71) **Applicant:** **LG ELECTRONICS INC.**, Seoul (KR)

(72) **Inventors:** **Seungho Baek**, Seoul (KR); **Huijae Kwon**, Seoul (KR); **Minha Lee**, Seoul (KR); **Hyein Jung**, Seoul (KR); **Yunseo Jang**, Seoul (KR)

(73) **Assignee:** **LG ELECTRONICS INC.**, Seoul (KR)

(**) **Term:** **15 Years**

(21) **Appl. No.:** **35/503,473**

(22) **Filed:** **Feb. 9, 2017**

(80) **Hague Agreement Data**

Int. Filing Date: **Feb. 9, 2017**

Int. Reg. No.: **DM/094854**

Int. Reg. Date: **Feb. 9, 2017**

Int. Reg. Pub. Date: **Aug. 11, 2017**

(30) **Foreign Application Priority Data**

Aug. 12, 2016 (KR) 30-2016-0039734

(51) **LOC (11) Cl.** **23-04**
